UNITED STATES PATENT OFFICE.

CHRISTIAN BAUMBACH, OF HANOVER, GERMANY.

COMBINED CIGAR CUTTER AND LIGHTER.

1,068,300.

Specification of Letters Patent. Patented July 22, 1913.

Application filed March 16, 1912. Serial No. 684,200.

To all whom it may concern:

Be it known that I, CHRISTIAN BAUMBACH, a subject of the German Emperor, residing at Hanover, in Germany, have invented a certain new and useful Improvement in Combined Cigar Cutters and Lighters, of which the following is a specification.

This invention essentially consists in combining a cigar cutter with an automatic lighter of the cerium-iron or equivalent type in such manner that the operation of cutting a cigar is automatically followed by the ignition of a burner for lighting the cigar.

One form of construction of this combined cutter and lighter is illustrated in the accompanying drawing, in which—

Figure 1 is a side elevation of the device, and Fig. 2 a vertical section thereof. Fig. 3 is a side view of the lighter, by itself, and Fig. 4 a vertical section of the part containing the cutter.

In its external shape the apparatus illustrated resembles a miniature Browning pistol, the cigar cutter being arranged partly in the butt *a*.

The cutter comprises an angular knife *b* pivoted to the butt *a* at *m*, with its cutting edge inside the butt and its back normally protruding approximately in the position of a pistol trigger, the knife being held in this normal position by a spring *d*. The butt *a* has a hole *c* for insertion of a cigar end, placed so that by pressing the knife

35 the inserted tip of the cigar can be cut off. A casing *e*, closed at the back, is attached to the top of the butt *a* and incloses a fuel container *f* which can be pushed in from the front and may contain cotton wool or 40 the like soaked with benzin. The container *f* is fastened by means of a screw stopper *g* inserted into the filling aperture through a hole in the rear wall of the casing *e*, so that the screw locks the container to the 45 casing. A small tube *p* fixed inside the container contains a spring *q*, which thrusts a piece of cerium-iron *n* to the front end of the said tube *p*. The container *f* is integral with a burner *o* which projects from the 50 front end of the casing, when the latter is open.

The casing *e* is normally closed by a cap *k*, which is pivoted at *i* to lugs on the casing, and contains a toothed friction wheel *h* centered at *i* and located below the burner

o and in front of the tube *p*. This cap can rock downward about its pivot, so as to expose the front of the casing and a spring *s* tends to rock the cap downward in this manner, and rotate the wheel *h*, but the cap 60 is normally held in closing position by a double-armed lever or catch *l*, which is pivoted at *m* and rests on the upper part of the knife *b*, so that the spring *d*, acting on the knife, thrusts the front arm of the lever 65 *l* against a notch at the bottom of the cap.

When the knife is actuated for cutting, it lifts the rear arm of the lever *l* and lowers the front arm, so that the cap can swing down. At the same time the friction wheel 70 *h* rotates in contact with the cerium-iron *n* and produces sparks so that at the end of the cutting operation, when the burner *o* is exposed, the vapor issuing from the burner 75 is ignited and produces a flame at which the cigar can be lighted.

What I claim as my invention and desire to secure by Letters Patent of the United States is:—

1. A combined cigar cutter and lighter 80 comprising a fuel container, a burner, a hinged cap normally covering said burner, a frictional spark producing device, adjacent said burner, a spring for collectively opening said cap and actuating said spark producing device, a catch for retaining said cap in closed position, and a cigar cutter comprising a movable blade carrying member adapted to release said catch in the 85 course of the cutting operation. 90

2. A combined cigar cutter and lighter comprising a barrel-shaped casing, a fuel container in said casing, a hinged cap for closing said casing, a burner on said container, a frictional spark producing device 95 adjacent said burner, a spring for collectively opening said cap and actuating said spark producing device, a catch for retaining said cap in closed position, a butt-shaped holder attached to said casing and having 100 a hole for insertion of a cigar end, a pivoted cigar cutting knife working in said holder, and a spring bearing on said knife so that the knife back normally protrudes from said holder and the knife holds said 105 catch in operative position.

3. A combined cigar cutter and lighter comprising a barrel shaped casing, having a hole, a fuel container having a filling aperture in said casing, a screw stopper adapt- 110

ed to pass the hole in said casing into the said filling aperture, to lock the container to the casing, a burner, a hinged cap normally covering said burner, a frictional 5 spark producing device adjacent said burner, a spring for collectively opening said cap and actuating said spark producing device, a catch for retaining said cap in closed position, and a cigar cutter comprising a movable blade carrying member adapted to re-

lease said catch in the course of the cutting operation.

In witness whereof I have signed this specification in the presence of two witnesses.

CHR. BAUMBACH.
